GEORGE B. MULLEN AND JAMES H. MULLEN, OF BAYSIDE, NEW YORK.

COMBINED BLOTTER AND PENWIPER.

Application filed August 19, 1921. Serial No. 493,596.

To all whom it may concern:

Be it known that we, GEORGE B. MULLEN and JAMES H. MULLEN, citizens of the United States, and residents of Bayside, in the county of Queens and State of New York, have invented a new and Improved Combined Blotter and Penwiper, of which the following is a full, clear, and exact description.

10 This invention relates to an improvement in stationery requisites and refers more particularly to a combined blotter and pen wiper, having for one of its principal objects the association of said elements for the purpose of convenience in that the drying of the ink and the wiping of a pen are closely allied operation.

As a further object the invention seeks to provide as a new article of manufacture 20 a combined blotter and pen wiper in which the pen wiper constitutes a convenient handle for picking up the blotter from a flat surface such as the top of a desk or the like.

25 The invention further contemplates as an article of manufacture an extremely simple and inexpensive article of stationery in the nature of a novelty which may be employed as an advertising medium.

30 With the above recited and other objects in view the invention resides in the novel combination and arrangement of elements set forth in the following specification, pointed out in the appended claims and illus-

35 trated in the accompanying drawing, it being understood that variations and modifications which properly fall within the scope of the claims may be resorted to when found expedient.

40 In the drawing—

Figure 1 is a plan view of a combined blotter and pen wiper illustrating the manner in which the pen wiper may be em-

ployed as a handle for lifting the blotter.

Fig. 2 is a fragmentary longitudinally 45 sectional view therethrough.

Referring to the drawings by characters of reference, 10 designates a blotter constructed from any suitable blotting material and of any desired configuration to which 50 a pen wiper 11 is attached, preferably to one end or side thereof by a fastening means 12 which may be a staple or any other suitable fastening means such as stitching or glue. Preferably the body of 55 the pen wiper will project from one of the side edges of the blotter in order to position the same conveniently for the wiping operation of the pen and to afford a handle for readily picking up the blotter from a 60 flat surface such as the top of a desk or the like. By combining two articles of this character in substantially the manner described a convenient stationery requisite is provided, the uses of which are closely al- 65 lied in that the user upon drying the ink with the blotter will have simultaneously located the pen wiper.

Having thus described our invention, what we claim is:

1. As a new article of manufacture, the combination with a blotter, of a pen wiper attached to the blotter and projecting from one edge thereof to constitute respectively a handle for facilitating the picking up of 75 the blotter and an element for wiping the pen.

2. As an article of manufacture, a stationery requisite comprising a blotter and a pen wiper secured thereto having its main 80 body portion projecting from one side edge of the blotter to constitute a pen wiping element, and a handle for picking up the blotter.

GEORGE B. MULLEN.
JAMES H. MULLEN.
